ROOFING CLEAT

Frederick C. McClanahan, Homer, La., assignor of
one-half to Hollace H. Bain, Homer, La.

Application December 10, 1932, Serial No. 646,686

5 Claims. (Cl. 108—33)

This invention relates to a roofing cleat primarily adapted to be used with roll roofing but may be used with any other slabs of flexible roofing.

5 The object of this invention is to provide a roofing cleat which is so constructed and applied that the nails are not exposed to the action of varied climatic conditions to become loose and cause leaks and to further provide a cleat that 10 also serves as a binder for the edge of the roofing, which is easily applied, inexpensive and presents a neat appearance on a finished roof. Other advantages and objects will become evident as the description proceeds.

15 Referring to the accompanying drawing, which is made a part hereof and on which similar reference characters indicate similar parts,

20 Figure 1 is a plan view of the cleat showing the securing clips in different positions as applied to overlapping roofing sheets,

Figure 2, a section on line 2—2 of Figure 1,

Figure 3, a perspective detail section of the cleat,

25 Figure 4, a plan view of application of the cleat in a vertical flush joint, and

Figure 5, a section on line 5—5 of Figure 4.

30 In the drawing reference numeral 10 indicates the roofing cleat formed of sheet metal consisting of a flat portion 11 of any suitable length provided with an upturned or angled edge 12.

35 The edge 12 is provided with a plurality of clips 13 at spaced intervals formed with a connecting neck 14, an enlarged stamped disk portion 15 having a cup-like center and a projecting tip 16. The clips 13 are adapted to be bent over parallel to the portion 11 and spaced apart the distance equal to the width of the upturned edge 12. The portion 11 is further provided with slots 17 having upturned lips 18 into which the tips 16 may be bent and inserted as clearly shown in Figure 10 2.

15 An opening 19 is provided in the portion 11 directly beneath the disk 15 through which a nail 20 or any other suitable securing means may be driven to hold the cleat in place.

15 In the application of the cleat 10 to roofing as disclosed in Figures 1 and 2, numeral 21 indicates the base of any suitable character to which the roofing is applied. A sheet of roofing 22 is laid on the base and the cleat is placed along the top, spaced from the edge and is secured by 10 nails 20 or any other suitable securing means driven through the openings 19. A second sheet of roofing 23 is placed with its bottom edge resting against the upturned edge 12 of the cleat.

15 Cement or roofing compound may be applied un-

der the edge of the layer of roofing 23 on the portion 11 of the cleat before the clips are bent in place. The angled edge 12 serves to prevent the compound from flowing downward to make an unsightly appearance at the lap. The cleats 60 13 are bent over with the tips 16 puncturing the layer of roofing 23 and into the slots 17, thus securing the edge of the roofing in place and prevent wind or rain from blowing under the lap. This construction or application just described has particular reference to lap joints. 65

In vertical flush joints where the edges of the roofing are simply brought together, the following construction is used. Reference is now made to Figures 4 and 5. A metal channel strip 24 is 70 secured to the base 21 by any suitable means such as nails 25 with the center along the seam of two adjacent sheets or slabs of roofing 26. Two cleats 10 are placed in the channel strip 24 and secured by nails 27 with the angled edges 75 12 back to back. The edges of sheets 26 rest against the angled edges 12 and the clips 10 are bent and secured in the manner previously described. As in the lap joint construction, cement or roofing compound may also be used in a similar manner to make the joint more secure. 80

In the above described construction it may be clearly seen that the nails or securing means are completely concealed and the effects of the outside elements in no way affect and cause the nails to become loose thereby causing leaks. It is possible in using the type of cleat in laying roll or sheet roofing to lay the roofing with much less pitch per foot of elevation than in other known cleat fasteners. The angle edge 12 will stiffen 85 the metal considerably, causing it to lay flat on roof, and with roofs of more than four inches or so of pitch, nailing will be necessary only under every other clip and on flat roofs or those with less than four inches pitch, nails should be 90 applied under every clip to produce the most satisfactory results.

The cleat is formed of any material suitable for the purpose and of a convenient length to handle, preferably of a length so they may be 100 shipped in the center of roll roofing direct from the manufacturing plant. The cleat above described is so designed and constructed to practically eliminate the waste of material in manufacturing the same, decrease labor in installation, 105 requires the use of fewer nails than is used in the present form roofing and results are such that a very satisfactory finish job may easily be obtained.

110 It will be obvious to those skilled in the art

that various changes may be made in my device without departing from the spirit of the invention and therefore I do not limit myself to what is shown in the drawing and described in the specification, but only as indicated by the appended claims.

Having thus fully described my said invention, what I claim as new and desire to secure by Letters Patent, is:

10 1. A roofing cleat for use in laying roll roofing material comprising a strip having a continuous angled edge, a plurality of clips formed on said edge, slots in said strip opposite said clips positioned to receive the tips of said clips as they are bent over and driven through the roofing material to secure said tips in fixed position beneath said strip, substantially as set forth.

20 2. A roofing cleat for securing roofing material in place comprising a relatively long strip having a plurality of spaced clips formed along one edge, said strip being further provided with slots therein opposite said clips, said slots being provided with upturned lips along one side, openings formed in said strips intermediate said slots and said edge to receive securing means for holding said cleat in place, the free ends of said clips adapted to be bent over the edge of the roofing, puncture the roofing and engage under said lips to firmly hold said clips in fixed position, substantially as set forth.

30 3. A cleat adapted to be applied to the edge of roofing comprising a strip having spaced slots

formed therein and having one edge turned upwardly at right angles thereto, clips formed on said edge adapted to be bent parallel to said strip over the edge of the roofing, said clips having tapered ends adapted to be bent and driven through the roofing to engage said slots to hold the edge of the roofing in fixed position, substantially as set forth.

4. A cleat adapted to be applied to the edge of roofing comprising a strip having clips provided with disk central portions formed on one edge adapted to be bent over the edge of said roofing parallel to said strip, said strip being further provided with separate perforations therein for receiving fastening means and the end of said clips after being driven through the roofing and so positioned that the fastening means are concealed by the roofing and are directly beneath the disk portions of said clips, substantially as set forth.

5. A cleat adapted to be applied to the edge of roofing comprising a strip formed with a continuous angled edge and a series of spaced slots therein, said edge being provided with a series of clips adapted to be bent over the edge of the roofing with the tips of said clips driven through the roofing and into said slots and fastening means driven through said strip intermediate said slots and clips to hold the strip in place at intervals directly beneath the clips and under the roofing material, substantially as set forth.

FREDERICK C. McCLANAHAN.
